THOMAS W. PROSSER AND JOHN H. WAHLBECK, OF KANKAKEE, ILLINOIS, ASSIGNEES
TO PARAMOUNT TEXTILE MACHINERY CO., OF CHICAGO, ILLINOIS, A CORPORATION
OF ILLINOIS

HOSIERY FINISHING APPARATUS

Application filed July 11, 1928. Serial No. 291,962.

This invention primarily relates to hosiery finishing apparatus; it involves a system for circulating a heating agent through one or more forming instrumentalities or so-called 5 drying and shaping forms; and it especially contemplates means for swiveling each of the forms on its respective support to facilitate the "boarding" operation, inspection by the operator, etc.

10 The present-day practice of finishing hosiery—drying, shaping, and creasing it— involves quite generally the employment of a series of forms or "boards" provided with crease-producing edges and adapted to be 15 interiorly heated, and on which the hosiery is "boarded" (as it is usually called), the forms usually being stationarily mounted in line on a support, such as a table, in order that the articles of hosiery may be success- 20 sively placed on the forms by the operator and then, when finished, stripped therefrom.

Various heating media are employed for 25 heating the forms to enable them to function as finishing instrumentalities. The present concept especially contemplates the use of a heating medium, such as hot water, steam, or other fluid, though it is within the principles of our concept that electricity may similarly be used for the purpose.

30 We have discovered, and our invention is predicated upon the discovery, that it is, at times, advantageous to change the position (momentarily, say) of the forms so that their rear surfaces—those which normally face 35 away from the operator or "boarded"— may be swung to the front or, if need be, to any selected angle. To that end, we have provided a novel type of swiveling-device to be interposed between a form and the sup- 40 porting structure therefor; this device including simple means for retaining the form in any of a plurality of possible positions—normal and abnormal—and also with means for facilitating the turning of the form on its respective swivel; this being accomplished 45 readily and conveniently without disturbing or otherwise interfering with the supply of the heating medium to the form or its withdrawal therefrom, and without danger of 50 leakage of the heating medium. We have,

thus, provided for the swiveling of the form without having to employ a packed or ground joint between the form and the conduits which supply and discharge the heating me- 55 dium to and from the forms.

In order that our inventive-concept may be more readily comprehended, we have illus- 60 trated the same in the accompanying drawings; but it is to be understood that in this disclosure, these drawings are to be 65 regarded as merely illustrative, that the invention is susceptible of other embodiments and utilizations, and that even the particu- 70 lar embodiment herein revealed is capable of a wide range of variation and modification 75 without departing from the underlying principles of the invention or sacrificing any of its salient features.

In these drawings:

Fig. 1 is a fragmentary view, in perspective, of the apparatus constructed in accordance with our inventive-concept, and showing two sets or rows of forms, one of these, in the front row, being illustrated in normal, boarding position; others at different angular positions; and another in a position re- 75 versed to that which it normally occupies;

Fig. 2 is a view in vertical cross-section, on the line 2—2, Fig. 1;

Fig. 3 is a fragmentary view, in sectional elevation and on an enlarged scale, of the structure with one form, this being shown partly broken away;

Fig. 4 is a view in cross-section of the form mounting; and

Fig. 5 is a view similar to Fig. 3, of a modification, and wherein hot water or the like is employed instead of steam.

Referring to these drawings, the reference-character 1 designates a finishing instru- 90 mentality of the general type shown and described in United States patents of George Collis No. 1,114,966, dated October 27, 1914, and No. 1,204,945, dated November 14, 1916; and in United States patents of Walter D. 95 Bütz, No. 1,207,494 and No. 1,207,496, dated December 5, 1916.

Preferably and as shown, these forms are used in one or more series, and it is to be understood that our invention is applicable 100

either to a double series of the forms, as shown in Fig. 1, for instance, or to a single series thereof.

Also preferably and as shown, a general 5 supporting structure or member, designated generally by the reference-character 2, is associated with the forms; this comprising an elongated central member 3, cross-pieces 4 on which the member is mounted; legs 5 depending from the cross-pieces; and braces 6 connected to the legs.

Mounted on the cross-pieces, at opposite sides of the supporting member, are troughs 7 for holding or storing stockings. As 15 shown, the troughs are of approximately the same length as the supporting member. The latter, in conjunction with the cross-pieces, supporting member, etc., constitute what may herein be referred to for identification purposes as a table. Mounted to travel on the upper edges of the side-walls of each trough is a rolling shelf 7^a.

Mounted in spaced-apart relation on the central member 3 is a series of swivel devices, marked generally 8, each of these comprising a tubular bearing-element 9 welded or otherwise secured to the central member 3, and occupying a position slightly inclined to the vertical, as shown in Fig. 2, for a purpose 30 to be described. The upper end of the bearing-element 9 is provided with an incut 10, preferably of V-shape formation, for a purpose presently to be explained.

Rotatably mounted within the bearing-member 9 is a pivot-post 11 of lengthwise dimensions preferably greater than that of the member 9, and carrying at its upper end a cross-pin 12 adapted to ride upon the upper edge of the member and, also, periodically 40 to seat in the V-shaped incut 10. The post carries, at its lower end, a flanged bolt 13. Between the flange thereon and the lower end of the bearing-member 9 is interposed a spring 14, the function of which is to cause 45 the cross-pin 12 to bear, with a certain degree of pressure, on the upper end of the bearing-member and, thus, to insure the cross-pin seating in the incut and be retained therein so as to hold parts associated with the swivel 50 device in operating position.

Rigidly secured to the upper end of the pivot-post 11 is a form-attaching element 15, the point of securement of the post to the element being adjacent one end of the element so that the major portion thereof extends beyond the post. As shown in Fig. 4, the post is secured to the element 15 at a slight angle, that is, at an angle to the vertical, so as to effect angulating of the position of the form, as will be explained farther on. Preferably and as shown, the attaching-element 15 is semi-circular in cross-section to present an upper curved surface 16, and 65 to this a correspondingly formed base-por-

tion 17 of the hollow hosiery-finishing form 1 is suitably secured, as by bolts 19-19.

Extending from the outstanding end of the attaching-element 15 is a handle 20 to facilitate the swinging movement of the 70 element.

Threaded into, or otherwise secured in, the attaching-element 15, to one side of the post 11, is a pair of nipples 21 and 22. Upstanding from the attaching-element and in fluid 75 communication with the nipple 21 is a third nipple 23, this being in fluid communication with the interior of the form 1. The latter, preferably and as shown, is provided with a longitudinal partition 24 which divides the 80 interior of the form into an inlet-channel 25 and a drains-channel 26. The base 17 of the form has two vertical ports 27 and 28, these being in communication at their lower end through an aperture 27^a for the outflow of 85 condensate that may accumulate around the nipple 23. The nipple 23 extends into the port 27 and communicates with the channel 25. The channel 26 is, by means of the port 28 in the base, in fluid communication with 90 the upper end of the nipple 22.

Preferably and as shown, flexible pipes or tubing 29 and 30, respectively, are attached at one end to the nipples 21 and 22, respectively, and at the opposite end to supply and 95 drains pipes not herein shown but which may be of the general construction and perform in the manner disclosed in United States Letters Patent 1,755,334, granted to Thomas W. Prosser, April 22, 1930, these various components constituting a circulatory system for the handling of the heating-fluid, condensate therefrom, etc.

The structure herein disclosed lends itself quite readily to the handling of either hot 105 water or steam; in fact, any suitable fluid; or even hot air. Where it is utilized in connection with hot water or the like, the arrangement shown in Fig. 5 is preferably though not necessarily used: In this instance, a nipple 31 (corresponding to the nipple 23 in Fig. 3) is disposed in the right-hand channel 32 of the form and a pipe or elongated tube 33 upstands therefrom and functions in the manner explained in the pending application of Joseph G. Prosser, filed February 110 9, 1926, Serial No. 87,164. The form-attaching element 15, in this embodiment, also has pendent nipples 34 and 35, to which are attached pipes corresponding with or similar to the flexible tubes 29 and 30, shown in Fig. 3.

Operation.—Inasmuch as the operation of the structure thus far described will be practically self-evident, it is not deemed necessary to detail the same to any extent: Suffice it to say, therefore, that, assuming that any selected form is in normal, boarding position—that is, with its side faces disposed in 115 parallelism with the central member 3 and 120 125 130 135

the troughs 7—and it be desired to swing that form into a different position, either angular to the supporting member and the troughs, or so that the toe-portion of the form will extend toward the right rather than toward the left, the operator, grasping the handle 20, swings the attaching-element 15 on its pivot—constituted by the elements 9 and 11—and in so doing the cross-pin 12 rides out of the incut or seat 10 and onto the upper edge of the tubular member 9, it being caused to bear hard against the same by reason of the pressure exerted thereon through the spring 14. This will suffice to hold the form in its shifted, angular position. If, for any reason, it be desired to swing the form farther around, this may be done, whereupon the cross-pin 12 will again seat in the incut 10; but, then, the toe-portion 20 of the form will extend toward the right.

In the meantime, and during this operation, by reason of the flexibility of the tubings 29 and 30, the supply of the heating fluid to, and the removal thereof and the draining of 25 condensate from, the forms will not be disturbed or at all interfered with.

This construction presents several advantages over known existing structures of more or less analogous type, wherein a ground or 30 packed joint is employed. The difficulty with a packed joint, as has been determined in practical experience, is that if the packing is made sufficiently tight to prevent leakage at the joint, it imposes considerable friction 35 on the revolving member of a swivel. On the other hand, if a ground joint is employed, there is a tendency in this to leak after being subjected to a certain amount of wear, and particularly if there is any scale 40 in the heating medium. In our construction, where we employ supply and drains tubings 29 and 30, respectively,—and which may be made of rubber, metal, or the like—the structure is leak-proof and permits the respective 45 forms to be turned freely.

It will be noted that as the pivot of the swivel device is located considerably to one side of the medial portion of the attaching-element 15, the axis of the device is offset to 50 and eccentric from the longitudinal axis of the form itself. By reason of this arrangement, a better balance is afforded to the form, additional leverage is obtained that makes for easier turning of the form on the swivel device, and the supply of the heating fluid to 55 and its withdrawal from the channels in the form will be more direct, with consequent improvement in the heating of the form by the fluid. Moreover, this arrangement permits the forms to be swung over the proximate trough, the rolling shelf on which is preferably in a plane below that of the lower 60 edge of the attaching-element, so that the shelf and any hosiery-articles on it will clear it. In consequence of this construction and

arrangement, the tables can be built narrower than heretofore, with a considerable saving in floor space, and this arrangement also materially shortens the reach of the operator in putting the stocking on the form and stripping it therefrom. 70

The cross-pin 12 on the post 11 has two seating positions in the incut 10 and, thus, two stops for the swivel are provided; that is to say, when the pin occupies the position shown in connection with the form at the left-hand end, in Fig. 1, this form is held with considerable rigidity during the operations of boarding. Then, if the form is swung 180 degrees from that position, the pin will again 80 seat in the incut and the form be firmly held while being inspected and/or sponged on its side which normally faces away from the operator.

In addition, the forms may be rotated, say, 85 to 180° and yet the proximate forms will be "clear" from each other. This is due to the angular relation which the post 11 bears to the form-attaching element 15, as shown in Fig. 4 and described above, and by reason of 90 which the form is, when turned on the pivot, shifted out of a vertical position to one which is slightly angular thereto, as shown in dotted lines in Fig. 4. It is not infrequently 95 of advantage to turn the forms to approximately 180° so as to present to the view of the "boarder" the entire surface thereof which normally faces away from her, rather than at an angle substantially less than 180° which gives to the boarder a perspective, and 100 sometimes unsatisfactory, view; the 180° position enabling her to readily perceive wrinkles or other irregularities in the fabric. In practice, it has been found that even a variation of a few degrees from the 180° position 105 is quite noticeable because, then, the operator's view is perspective, so to speak, and the light does not fall squarely on the surface which she must inspect. The 180° position- 110 ing of the form also facilitates the practice of "sponging" the fabric where this is done, in connection with ingrained hosiery, for instance. If two proximate forms were to be 115 swung into engagement on their respective swivel devices, there would be a resulting damage to the fabric and, particularly, where it is of the so-called chiffon or sheer type. This arrangement also permits the forms to be mounted closer together, in consequence of 120 which the length of the table may be materially reduced. If the construction were otherwise, the forms could only be turned at an angle less than 180°, or, if this full turning were essential, it would be necessary to 125 make the table much longer, and that would obviously require considerably more floor space.

The provision of the handle 20 on the attaching-element 15, as already stated, facilitates the turning of the form to any selected 130

angle. In addition, it obviates the necessity for the operator grasping any portion of the form itself and, particularly, where it is covered by the stocking. Where an operator has to grasp the stocking-covered form, there is a tendency to disarrange the stocking on the form, and if this is done after the fabric is "set", the result is "poor boarding".

Other advantages and desirable features of this construction will be manifest and, particularly, to those who have had experience in operating hosiery-finishing forms which involve a different principle of swiveling and, thus, embody a different type of swivel device.

It will be apparent that the principle of our concept can be equally well employed in connection with electrically heated finishing forms and which, in lieu of the supply and drains hose 29 and 30, would employ electrical conductors connected to a suitable source of supply of current.

What we claim is:

1. A hosiery-finishing structure including, in combinative association, an elongated support, a series of bearing members thereon, and occupying a position slightly angular to the vertical, a swivel-post rotatable in the bearing-member, a form-attaching element on each post, the member and post being angular to each other, and a series of finishing forms on the attaching elements, the rotative movement of the forms resulting in these being moved from a normal position substantially vertical to an off-normal position angular to the vertical, whereby proximate forms are, at their upper extremities, spaced from each other.

2. A hosiery finishing structure including a support, a series of bearing elements secured to said support, a series of form-attaching elements juxtaposed to said support and each provided near one end with a pivot post rotatably mounted in one of said bearing elements, and a hosiery drying form mounted on each of said form-attaching elements with the longitudinal axis of the form offset from and eccentric to its respective pivot post, whereby to vary the angular relation of adjacent forms when one of them is rotated on its pivot post.

3. A form-supporting structure including, in combinative association, a swingable form-attaching-element, a pivot-device therefor, means for maintaining the element in any of a plurality of adjustable positions, juxtaposed inlet and drains-nipples depending from the element, and elongated flexible conduits connected to the nipples.

4. A form-supporting structure including, in combinative association, a swingable form-attaching-element, a pivot-device therefor, means for maintaining the element in any of a plurality of adjustable positions, juxtaposed inlet and drains-nipples depending

from the element, elongated flexible conduits connected to the nipples, and a tubular instrumentality upstanding from the element and in fluid communication with one of the nipples.

5. A swiveled form-supporting structure including, in combinative association, a swingable form-attaching-element, a pivot-device therefor comprising a post depending therefrom, a post-encompassing member for mounting the post, coacting means on the post and member for retaining the swingable element in any of a plurality of adjustable positions and including an instrumentality interposed between the member and post for tensioning said post and member, and an elongated support to which the encompassing member is connected.

6. A hosiery finishing structure including a support, a bearing element secured to said support, a form-attaching element juxtaposed to said support and provided near one end with a pivot post seating in said bearing element, an incut in said bearing element, a pin on said pivot post, and means urging said pin into said incut.

7. A hosiery finishing structure including a support, a bearing element secured to said support, a form-attaching element juxtaposed to said support and provided near one end with a pivot post seating in said bearing element, intake and drain nipples on said form-attaching element to one side of said pivot post, and a hosiery drying form mounted on said form-attaching element and in fluid communication with said nipples.

In testimony whereof we affix our signatures.

THOMAS W. PROSSER.
JOHN H. WAHLBECK.
